UNITED STATES PATENT OFFICE.

HENRY J. STEVENSON, OF NORTH ANDOVER, MASSACHUSETTS, ASSIGNOR TO DAVIS & FURBER MACHINE CO., OF NORTH ANDOVER, MASSACHUSETTS, A CORPORATION OF MASSACHUSETTS.

FILLET DRUM AND STAND.

Application filed April 1, 1926. Serial No. 98,957.

This invention relates to apparatus for applying fillet material to rolls such as are used in carding machines and more especially to friction devices used in connection with fillet drums to produce tension in the fillet material as it is applied to the roll. The present invention, as will hereinafter more fully appear, is applied to drums known to the trade as fillet drums upon which is wound a supply of material in a fillet form. Any desired material may be used, card clothing being illustrated herein.

One end of the material is attached to a roll upon which it is desired to apply the material. This roll is mounted in a stand and suitable means are provided for rotating the roll. As the roll is rotated, the material is wound spirally thereon, which operation causes the material to unwind from the fillet drum. A friction device associated with the drum maintains tension in the material.

The above-mentioned friction device consists of a friction drum rigid with the fillet drum about which is a friction band so arranged as to retard rotation of the fillet drum. Means are also provided to vary the retarding action of the friction device and means to indicate the degree of the said retarding action.

It is common practice to employ a friction device on fillet drums, which device is usually adjustable in order to vary the amount of tension upon the material. It can be readily understood from the foregoing that in order to obtain a desired tension upon the material through the use of friction on the fillet drum, it would require an experienced operator to approximate the desired tension by estimating the proper degree of friction upon the drum. One of the principal objects of my invention is to provide a means of accurately determining the amount of friction on the fillet drum and thus the tension in the material.

In friction devices of the type herein described there is always present the element of wear and consequent decrease in the effective friction. Another object of this invention is to provide means to readjust and maintain constant the degree of friction as wear occurs.

In applying card clothing or other material to rolls, it is, of course, desirable to apply it evenly throughout the length of the roll and also to produce a quantity of rolls

that are uniform in character. Another object of the present invention is to provide means for producing a uniform product by maintaining constant a predetermined tension on the material throughout the process of applying it.

A further object of my invention is to provide means of quickly applying and releasing the friction upon the fillet drum.

Other objects and features of the present invention will more fully appear from the following description and accompanying drawings and will be particularly pointed out in the claims.

In the drawings:

Fig. 1 is a side elevation of the apparatus for applying fillet material to rolls.

Fig. 2 is a side view of the fillet roll and stand with parts broken away showing the friction device and indicating means.

Fig. 3 is a cross section on line 3—3 of Fig. 2.

Fig. 4 is a detail view showing a portion of the friction band and the connection between the band and the indicating means.

Referring to the drawings, 1 indicates a fillet drum upon which is wound spirally and in a single layer a quantity of fillet material 2. This drum is mounted for rotation in a stand 3. A roll 4 upon which the fillet material is to be applied is rotatably mounted in a stand 5. Any means may be employed to rotate the roll but I have illustrated herein a hand-operated windlass consisting of a large gear 6 securable to the shaft of the roll 4. A pinion gear 7 is mounted for rotation upon the stand 5, said gear meshing with the gear 6. A crank 8 is rigid with the pinion gear 7 by means of which the large gear 6 is rotated, thus driving the roll 4.

Rigid with the fillet drum 1 is a friction drum 9. Surrounding the friction drum is a friction band 10 upon the free ends of which is mounted a toggle device adapted to vary the pressure of the friction band 10 upon the friction drum 9. Said device is also capable of quickly releasing and again applying the said pressure. The toggle device is composed of a tension member 11 secured to one end of the friction band 10 at 12. A pressure transmitting member 13 is slidably mounted upon the tension member 11, said tension member having a manually operated nut 14 upon the screw threaded

end 15 of the tension member 11. The nut 14 engages the pressure transmitting member 13 at 17. Upon the other end of the friction band is secured a fulcrum member 18. This member is provided with a pivot point 19. A similar pivot point 20 is formed upon the pressure transmitting member 13. Interposed between the pivot points 19 and 20 is a compression member 21. Said member receives pressure from the member 13, which pressure is applied by the nut 14 and delivers it to the end of the friction band, the other end of which is held by the tension member 11. Thus by adjusting the nut 14 the pressure of the friction band upon the friction drum may be varied.

It will be also noted that the intermediate pivot point 19 is out of line with the pivot point 20 and the point of connection 12 between the friction band 10 and the tension member 11, so that as pressure is applied to the band a component of the force due to the said pressure will cause the tension member 11 to bear against the fulcrum member 18. The parts as above described are in position such as shown in the full lines, Fig. 2, in which position they are locked together by the toggle action above described. However, when the parts are thrown into the position shown in dotted lines, Fig. 2, the toggle is broken and the pressure upon the friction drum is thereby released.

An arm 23 is secured to the friction band in any suitable way. This arm cooperates with the compression member 24 and the indicating means shown generally at 25 to hold the friction band 10 against rotation while the fillet drum is revolved. The compression member 24 has a flexible connection with the arm 23 as shown at 26. This compression member has likewise a flexible connection with one end of a lever 27. The lever 27 constitutes one member of a gravity-actuated balance. Said lever is fulcrumed at 28 upon a bracket 29 mounted upon the stand 3. The lever 27 is of the first class, the short arm of which is shown at 30 and the long arm at 31. A similar lever 32 is also fulcrumed upon the bracket 29 at 33, the said lever 32 having arms 34 and 35. The lever 32 is so positioned with relation to the lever 27 that the end of the arm 31 of the latter engages the end of the arm 34 of the former at 36. The sliding weight 37 is mounted upon the arm 35 of the lever 32.

As the fillet drum 1 is rotated, a force is produced by the friction between the band 10 and the drum 9. Said force is transmitted to the balance 25 through the arm 23 and compression member 24. The fulcrum points 28 and 33, also the point of engagement 36 between the lever arm 31 and the lever arm 34, are of special design. A piece of relatively thin spring steel is inserted in adjacent members forming the said

fulcrum points of said point of engagement 36 so that any pivotal movement of the parts will flex the steel pieces thus forming anti-friction bearings. The foregoing design also prevents the parts from getting out of adjustment. 70

The operation of the apparatus is as follows. A quantity of the fillet material is wound upon the fillet drum, one end of which is attached to the roll upon which the material is to be applied, said roll having previously been mounted in the stand 5. The material is then spirally wound upon the roll by means of the windlass, which operation causes the material to unwind from the fillet drum. When the roll has been completely covered with the material, it is secured in position by any suitable means. In order to maintain a predetermined tension upon the material as it is applied, the sliding weight 37 is set at the proper position on the arm 35 of the balance. The pressure of the friction band 10 upon the friction drum 9 is then so adjusted by the nut 14 that the above described force delivered to the balance 25 will just counterbalance the weight 37. It is apparent from the foregoing that any desired degree of friction and consequent tension in the material may be maintained by adjustment of the nut 14. 85

If it is desired to release the tension entirely, the tension member 11 is pulled manually into the position shown in dotted lines, Fig. 2, which breaks the toggle and thereby leaving the fillet drum free to rotate. To again restore the tension in the material, it is simply necessary to throw the parts back into position shown in full lines, Fig. 2. 100

Having thus described the invention, what is claimed as new, and desired to be secured by Letters Patent, is:

1. An apparatus for applying fillet material under tension to a roll comprising a support for the roll, means mounted upon the support adapted to rotate the roll, a fillet drum upon which is wound fillet material and from which it is unwound by the rotation of the roll, a friction drum rigid with the fillet drum, a friction band surrounding the friction drum, means for varying the frictional pressure between the friction band and the friction drum, indicating means and a compression member adapted to transmit the force tending to rotate the friction band to the said indicating means and thereby cause it to indicate the tension in the fillet material as it is wound on the roll. 115

2. In an apparatus for applying material in fillet form to a roll, the combination of a fillet drum upon which fillet material is wound and means to wind the fillet material upon the roll from the fillet drum of a friction drum rigid with the fillet drum, a friction band surrounding the friction drum, toggle means for adjusting the pressure of 120

the friction band upon the friction drum, said means being so constructed as to be capable of quickly releasing the said pressure and again restoring said pressure, a 5 gravity actuated balance consisting of a system of compound levers upon one of which is a sliding weight, an arm rigid with the friction band, a compression member interposed between the said arm and the 10 said gravity actuated balance whereby as the fillet drum is rotated in the process of unwinding the fillet material from the fillet drum, the force produced by the frictional engagement between the friction drum and 15 the friction band will be indicated upon the gravity actuated balance.

3. In an apparatus for applying material in fillet form to a roll, the combination of a fillet drum upon which fillet material is 20 wound and means to wind the fillet material upon the roll from the friction drum, a non-continuous friction band surrounding the friction drum, toggle means for adjusting the pressure between the friction band and 25 the friction drum comprising an adjustable tension member connected to one end of the friction band, a compression member adjustably connected at one end to the tension member and at the other end pivotally connected to the free end of the friction band, the latter pivot point being intermediate of its adjustable connection and the point of connection between the tension member and the friction band whereby, when the members of the said toggle means are so correlated that the intermediate pivot point is

to one side of a straight line between said adjustable connection and the connection between the friction band and the tension member, the mechanism will act to resist 40 the pressure applied between the friction band and the friction drum and also, when the said intermediate pivot point is on the opposite side of the said straight line, said pressure will be released, and means to indicate the said pressure between the friction band and the friction drum. 45

4. In an apparatus for applying material in fillet form to a roll, the combination of a fillet drum upon which fillet material is wound and means to wind the fillet material upon the roll from the friction drum, a non-continuous friction band surrounding the friction drum, toggle means for adjusting the pressure between the friction band and the friction drum comprising an adjustable tension member connected to one end of the friction band, a fulcrum member rigid with the other end of the friction band, a pressure transmitting member slidably mounted 50 upon said tension member, a pressure member having adjustable engagement with the said tension member and adapted to engage the said pressure transmitting member, a compression member interposed between the 55 said pressure transmitting member and the fulcrum member and means to indicate the degree of pressure between the friction band and the friction drum. 60

In testimony whereof, I have signed my 70 name to this specification.

HENRY J. STEVENSON.
